LAWRENCE M. ENDRES, OF CROSS PLAINS, WISCONSIN.

GANG-DISK GRINDER.

1,279,526.

Specification of Letters Patent. Patented Sept. 24, 1918.

Application filed March 9, 1918. Serial No. 221,464.

To all whom it may concern:

Be it known that I, LAWRENCE M. ENDRES, a citizen of the United States, and resident of Cross Plains, in the county of 5 Dane and State of Wisconsin, have invented certain new and useful Improvements in Gang-Disk Grinders; and I do hereby declare that the following is a full, clear, and exact description thereof.

10 My invention has for its primary object to provide a simple, economical and durable gang disk grinder, the arrangement and construction of which is such that the entire series of disks can be ground simultaneously without dismantling, it being contemplated to utilize the grinding machine either as a fixture or portable device, in which latter case the said device would be suitably mounted upon a truck whereby it 15 can be readily transported from place to place.

A further object of my invention is to provide means for adjustably supporting the entire gang of disks upon the frame, 25 whereby they will be positively and simultaneously fed to a series of grinding wheels also mounted upon the frame.

Another object of my invention is to provide a universal bar and yielding connections between the bar and grinder wheels, 30 whereby a compensating engagement between the entire series of said wheels and the disks can be effected.

A still further object of my invention is 35 to provide means for adjusting the grinder wheels with relation to the disks to be ground independently.

With the above and other objects in view the invention consists in certain peculiarities 40 of construction and combination of mechanical elements as hereinafter set forth with reference to the drawings and subsequently claimed.

In the drawings—
45 Figure 1 represents a face view of a grinder machine exemplifying one form of carrying out my invention, parts being broken away and in section to more clearly illustrate structural features;

50 Fig. 2, a cross-section of the same showing a gang disk harrow in light lines positioned to be operated upon by the grinding wheels, the section being indicated by line 2—2 of Fig. 1; and,

55 Fig. 3, an enlarged detailed sectional view of one of the grinder wheel units, the same

being shown positioned against a portion of a harrow or pulverizer disk to effect grinding operation.

Referring by characters to the drawings, 60 1 represents a skeleton frame provided with horizontally disposed brackets 2, the upper legs of which brackets are slotted as at 2' for the reception of spindle-supporting blocks 3 which are notched out to receive the 65 spindle 4 or hubs of the outer pair of disks 5, which are units of a series used in the ordinary type of disk harrow or pulverizer. Each of the blocks 3 is provided with a threaded ear 3' which is engaged by a screw- 70 threaded adjusting rod 6 that is provided with a cranked handle and is provided with suitable bearings in the bracket 2. This mechanism is to provide horizontal adjustment of the harrow spindle and its series of 75 cutting disks, whereby the edges of said cutting disks will be fed to the grinding units.

While I have shown the rods 6 arranged to be adjusted independently by their 80 cranks, it is manifest that these rods may be in link or gear connection so as to obtain a simultaneous adjustment of them.

The frame is provided with suitable end bearings for a shaft 7, which shaft, in this 85 instance, is provided with a power pulley at one end adapted to receive its drive from any suitable source not shown. A series of grinder wheels 8 are mounted upon the shaft 7 and are arranged to rotate with it, 90 but have adjustment axially thereof. My preferred arrangement of mounting the wheels 8 is best shown in Fig. 3 of the drawings, in which view it will be seen that the shaft 7 at the point of mounting of each 95 grinder wheel is provided with a key-way 7', which is slidably engaged by a key 9' that is carried by a sleeve 9. The sleeve is loosely mounted upon the shaft and has a slot therein for the reception of the key 100 9 which is dropped in position approximately flush with the outer face of said sleeve. In assembling the parts thereafter the grinder wheel 8 is slipped over one end of said sleeve against a collar portion 9" 105 thereof and a collar 10 is then adjusted over the sleeve against the juxtaposed face of the wheel. Thus the key 9' is held in position by these parts. The wheel is then secured by a binding nut 11 which is in threaded union with one end of the sleeve and adapted to impinge against the collar 10

110

whereby the grinder wheel is locked to the sleeve.

In order to effect longitudinal or axial movement of the grinder wheel assemblage, 5 I provide a hexagon collar or nut 11' which is also in threaded engagement with the sleeve end and is positioned with relation to the nut 11 so as to form an annular groove between these parts. The groove is adapted 10 to receive a pair of wear washers 12, between which is mounted a spanner ring 13 having sets of pins 13' projecting from opposite sides thereof. The pins 13' are engaged by the spannered end 14' of a lever 15 14, which lever is fulcrumed to the outer end of a bracket 15, the fulcrum being effected by the lever passing through an aperture in the end of said bracket. The turned up end of this bracket is apertured and mounted 20 upon a bolt 16 to permit slight longitudinal play on the bolt and connected to a hooked end of said bolt and an eye of the bracket 15 is a pull-spring 17, whereby the bracket is normally held by the spring pressure 25 against the face of an arm 18 which carries the bolt 16.

As best shown in Fig. 1, each of the arms 18 are right-angular in shape and the upper leg 18' in each instance is clamped to a universal adjusting bar 19 by means of an eye-bolt 20. The eye-bolt is provided with a hand-nut 20' which is in threaded union therewith and adapted to draw the parts tightly together through its engagement 35 with the upper surface of the bar 19, it being understood that the eye-bolts 20 pass through a slot in said bar, which slot is in this instance provided by the skeleton construction of the bar 19, it being formed in 40 two parts connected by suitable bolts and spacing thimbles. The eyed head of each bolt 20 forms a loose pivot connection for its corresponding lever 14. The universal bar 19 is adjustably mounted upon knees of 45 the frame, being guided and confined by studs 21'. One end of the universal bar 19 is engaged by a threaded spindle 22 having a hand-crank 22' at its outer end whereby the spindle is rotated to move the bar parallel 50 to the grinder wheel shaft, the spindle 22 having its bearing in a bracket with which the frame is provided.

Attention is directed to the fact that the wear washers 12, which constitute a part of the wheel hub assemblage, are provided for the purpose of replacement as the friction of the relatively movable and fixed parts in the groove may, from time to time, cause more or less wear and hence require renewal 60 of said rings.

In the operation, after the several spring-controlled adjusting units of the series of grinder wheels have been regulated so as to grind the disks upon one face as shown in 65 Fig. 3, power is applied to the drive shaft 7,

whereby the grinding operation upon this face is completed. In that type of flat disk wherein it is desirable to grind both faces, to grind the opposite face of the harrow disks from that shown in Fig. 3, it follows that the spring tension device comprising the arm 18 and bracket 15 must be reversed so as to permit the tension of the spring to force the grinder wheels in the opposite direction from that shown in Fig. 1 of the drawings. This reversal of the pressure of the springs is effected by loosening the hand nut 20' of each unit and thereafter the arm 18 of each unit is swung from right to left whereby the position of said arm is reversed from that shown in Fig. 1. The parts are then adjusted and the hand-nut is tightened so that the spring pressure will force the grinder wheels from right to left and thus the disks to be ground (which may be of any type) are then sharpened upon their reverse faces from that shown in Fig. 3. This operation is very simple to effect as it is only necessary to swivel the arms 18 upon their bolts and the brackets consequently will rotate with said arms. It is obvious that the disks to be ground can be arranged with any suitable driving connection from the shaft 7 whereby they may be intermittently or continuously rotated slowly about their axes so as to accomplish the desired result, it being preferable to use a crank driven by power from the shaft 7 with an intermittent ratchet feed upon the harrow disks.

While I have shown and described one form of my invention in all of its details, it is understood that the structural features of the exemplification fully explained may be varied within the scope of the claims as understood by the skilled mechanic.

Attention is also directed to the fact that, in the drawings, the grinding machine is fixed to a base, but it is understood that the frame can be so constructed as not to require anchorage. It is also contemplated to mount the frame upon a truck, whereby it can be transported from place to place convenient for the work that it is designed to accomplish.

In order to compensate the grinding pressure of the wheels upon the disks, each wheel is provided with independent adjusting means and pressure control. The tension of the springs 17 can be regulated to a certain degree and independent axial adjustment of each grinder wheel 8 can be effected by manipulating the hand-nuts 20', whereby the levers 14 are shifted with their fulcrums. After each wheel has been adjusted to the satisfaction of the operator, so as to obtain a uniform abrasive contact with relation to the disks, the entire gang of wheels can be simultaneously adjusted by movement of the universal bar through its manipulating threaded spindle 22.

Attention is further directed to the fact that as the grinding of the outer edges of the disks is accomplished, they may be fed up to the grinder wheels by the rods 6 in such manner that the tapered grinding faces of the wheels 8 are maintained indefinitely irrespective of wear.

I claim:

1. A gang disk grinder comprising a supporting frame for the disk spindle, a rotatable shaft mounted upon the frame, a series of grinder wheels revolute with and axially movable upon the shaft, a universal adjusting bar mounted upon the frame, an independent yieldable connection between the bar and each grinder wheel, and feed mechanism carried by the frame for effecting grinding engagement between the wheels and disks.
2. A gang disk grinder comprising a supporting frame adapted to receive without dismantlement the disks to be ground, a rotary shaft mounted upon the frame, a series of grinder wheels revolute with and axially movable upon the shaft, a universal adjusting means for the grinder wheels, and an independent adjusting means for each grinder wheel.
3. A gang disk grinder comprising a supporting frame adapted to receive without dismantlement the disks to be ground, a rotary shaft mounted upon the frame, a series of grinder wheels revolute with and axially movable upon the shaft, a universal adjusting bar, levers suspended from the bar and in spanner connection with the wheels, and a medially positioned yieldable fulcrum point for each lever carried by the bar.
4. A gang disk grinder comprising a supporting frame for the disk spindle, a rotatable shaft mounted upon the frame, a se-

ries of grinder wheels revolute with and axially movable upon the shaft, a universal adjusting bar mounted upon the frame, an independent yieldable connection between the bar and each grinder wheel, a pair of blocks slidably mounted upon the frame and adapted to receive the gang disk spindle, and threaded adjusting rods engageable with the blocks.

5. A disk grinder comprising a rotary shaft, an abrading wheel revolute with and axially movable upon the shaft, a lever in spanner connection with the abrading wheel hub, a bar, a shiftable pivot connection carried by the bar for the lever, a yieldable connection arranged medially of the lever carried by said bar, and means for adjusting the bar.

6. A gang disk grinder comprising a supporting frame for the disk spindle, a rotatable shaft mounted upon the frame, a series of grinder wheels revolute with and axially movable upon the shaft, a universal adjusting bar mounted upon the frame, and a reversible independent yieldable connection between the bar and each grinder wheel.

7. A gang disk grinder comprising a supporting frame adapted to receive series of disks to be ground, a rotary shaft, a series of hub abrading wheels revolute with and axially movable upon the shaft, a lever in spanner connection with the hub of each abrading wheel, a universally adjustable bar, a shiftable pivot connection carried by the bar for each lever, and an intermediately positioned fulcrum point for each lever carried by said bar.

In testimony that I claim the foregoing I have hereunto set my hand at Milwaukee, in the county of Milwaukee and State of Wisconsin.

LAWRENCE M. ENDRES.
